BREAST FLAP MOLDING MACHINE

Michele Cuozzo, Lynn, Mass., assignor to United
Shoe Machinery Corporation, Borough of
Flemington, N. J., a corporation of New Jersey

Application July 24, 1939, Serial No. 286,219

18 Claims. (Cl. 12—17)

This invention relates to machines for molding heel-breast-covering flaps to facilitate the permanent attachment of the flaps to the breasts of attached heels of shoes.

5 In the manufacture of shoes having Louis heels, for example, it is customary to split from the grain side of an unattached sole a flap which, after the sole and heel have been attached to a shoe, is adhesively secured to the breast of the attached heel. Since the forwardly projecting upper end of the breast of the heel is bowed transversely of the heel and is concave heightwise of the heel, the flap, which tends to lie flat, has to have the lateral margins of its base portion stretched lengthwise of the flap so as to conform said margins to the upper lateral portions of the heel breast. Moreover, the portion of the flap to be applied to the upper end of the heel breast usually has to be stretched widthwise to a considerable extent in order that it shall be wide enough to cover the upper end of the breast.

20 The previously tempered flap, the inner face of which has been coated with cement or other suitable adhesive, is commonly stretched by hand at the localities above referred to just prior to the application of the flap to the breast of the heel. Considerable time and effort are required to stretch the flap by hand. Moreover, the hand operation cannot be safely relied upon to stretch a thick flap beyond the limit of elastic recovery of the material of which the flap is made, with the result that the flap is not permanently stretched to the desired shape and therefore cannot be effectively secured to the breast of the heel.

25 Various machines for molding heel-breast-covering flaps have been proposed. None of such machines, however, in addition to stretching the lateral base margins of the flap lengthwise into conformity to the contour of the upper breast margins of the heel are adapted to stretch the base portions of the flap widthwise to varying extents, or independently of the above lengthwise stretching, in order to insure that the molded flap shall be wide enough to cover the upper end of the breast of the particular style of heel to which it is to be applied.

30 It is an object of the present invention to provide an improved machine for quickly and effectively molding heel-breast-covering flaps. With the above object in view, and in accordance with a feature of the present invention, the illustrative flap-molding machine comprises molding units constructed and arranged to stretch the

35 lateral base portions of a heel-breast-covering flap lengthwise, and means for moving one of said units away from the other to stretch the base portion of the flap widthwise.

40 The flap-molding units of the illustrative machine comprise matrices having aligned flat faces upon which the flap is positioned with its lateral base margins overlying recesses which are formed in the faces and are of increasing width and depth as they extend away from each other. In order to stretch the lateral base margins of the flap lengthwise and in increasing amounts toward the adjacent lateral edges of the flap so as to conform said margins to the lateral portions of the upper end of the heel breast, there are provided two rubber pads, which are secured to movable carriers, respectively, and force the lateral base portions of the positioned flap against the bottoms of the recesses.

45 To insure that the lateral base portions of the flap may be effectively stretched lengthwise without distorting adjacent portions of the flap, and especially the portion of the flap which is to be secured to the flat upright portion of the breast of the heel, the illustrative machine, in accordance with another feature of the invention, is provided with two pairs of rubber-covered clamps which force the flap with considerable pressure against portions of the flat faces of the matrices, which portions are located at opposite sides of the respective recesses, before and while the rubber pads are forcing the lateral base portions of the flap into the recesses. Two of the clamps are yieldingly mounted upon each of the carriers, the arrangement being such that as the carriers are moved downward toward their associated matrices the clamps force the flap against the flat faces of the matrices, and upon continued downward movement of the carriers the pads force the lateral base portions of the flap into the recesses and against the bottoms of said recesses.

50 In order permanently to stretch the base portion of the flap widthwise sufficiently to insure that it shall cover the upper end of the heel breast, each of the carriers, together with its associated matrix, is mounted for swinging movement, as a unit, away from the other carrier and matrix while the lateral base portions of the flap are gripped between the matrices and the clamps. The amount of widthwise stretching of the base portion of the flap is controlled by varying the extent of swinging movement of the corresponding carriers and matrices away from each other, stops being provided for limiting

- the outward limit of such movement. By mounting the associated carriers and matrices for swinging movement as above described the flap can be stretched widthwise to varying extents
- 5 independently of the lengthwise stretching of the lateral base portions of the flap, thereby insuring that the flap can always be stretched widthwise sufficiently to cover the upper end of the breast of any particular style of heel.
- 10 The carriers and their associated matrices may be initially adjusted with relation to each other to vary the amount by which the lateral base portions of the sole will be stretched lengthwise by the machine, in accordance with the shape
- 15 of the upper end of the breast of the heel to which the flap is to be applied.

The above and various other features of the invention will best be understood and appreciated by reading the following detailed description in connection with the accompanying drawings, in which

Fig. 1 is a perspective view, partly broken away, of the illustrative machine:

Fig. 2 is a side elevation, partly broken away, 25 of a portion of the machine as viewed in the direction of arrow II shown in Fig. 1;

Fig. 3 is a section on line III—III of Fig. 2;

Figs. 4, 5 and 6 are views partly on line IV—IV of Fig. 3 during three progressive stages of the flap-molding operation;

Fig. 7 is a perspective view of the heel end of a sole from which a heel-breast-covering flap has been split;

Fig. 8 shows the sole of Fig. 7 after its heel-breast-covering flap has been molded by the above machine; and

Figs. 9 and 10 are perspective views of the heel end of a shoe the heel-breast-covering flap of the attached sole of which has been molded by the above machine.

The illustrative machine will be described with reference to molding heel-breast-covering flaps 20 split from soles 22 in order to facilitate the adhesive attachment of the flap to the breasts 24 (Figs. 9 and 10) of Louis heels 26 of shoes 28 to which the soles are attached. The flap 20, shown in Fig. 7, may be molded to the shapes shown in Figs. 8, 9 and 10 by the machine either before or after the attachment of the sole 22 to the shoe 28.

Since the unmolded heel-breast-covering flap 20 shown in Fig. 7 is split from the flat heel-seat portion of the sole 22 it tends to lie flat and resists to a considerable degree, even while in temper, attempts to conform it to the upper end or the forwardly projecting portion 30 (Fig. 9) of the breast 24 of the attached Louis heel 26 of the shoe 28, which upper end is convex transversely of the heel and concave heightwise of the heel. When the operator adhesively secures the tempered flap to the lateral margins of the upper end 30 of the breast of the heel without first stretching the lateral margins of the base portion of the flap lengthwise beyond their limit of elastic recovery, such flap has a tendency, especially after it becomes dry, to spring away from the upper lateral margins of the heel breast.

With the above considerations in view the illustrative machine comprises a pair of matrices 32, two pairs of clamps 34 for forcing the flap 20 against the matrices, and conformable rubber pads 35 which cooperate with the respective matrices and clamps to stretch the lateral margins of the base portion of the flap lengthwise of the flap beyond the limit of elastic recovery of the

material of which the flap is made, thereby molding the flap to the proper shape to be effectively applied to the upper lateral margins of the breast of the heel.

The respective matrices 32 are provided with recesses 36 which are of increasing width and depth as they extend away from each other and from the central vertical plane 38 of the machine. The pads 35 are provided with upwardly extending flanges 40 (Fig. 1) which fit in vertical recesses 42, respectively, of carriers 44 and are secured to the carriers by pins 46. As will appear later, the carriers 44 yieldingly support the clamps 34 and are lowered in rectilinear paths causing the clamps to force the flap against portions of flat knurled faces 48 of the matrices, which portions are located at opposite sides of corresponding recesses 36, as illustrated in Figs. 3 and 4, and then causing the pads 35 to force the lateral base margins of the flap against dished serrated faces or bottoms 50 of the recesses 36 of the respective matrices 32, as illustrated in Fig. 5, so as to stretch said margins of the flap lengthwise, the stretching force increasing progressively from the central region of the flap outward. Crimps 51 (Figs. 8 and 9), formed in the lateral base portions of the flap as a result of the above molding operation, extend widthwise of the flap and increase in width and height as they approach the adjacent lateral edges of the flap.

At the heel-breast line 52 (Fig. 10) of the shoe 28 the attached sole 22, the unmolded flap 20, and the front edge 54 of the forwardly projecting portion of the breast of the heel are of approximately the same projected width as seen looking toward the bottom of the shoe. It will be appreciated, however, that since the upper end 30 (Fig. 9) of the heel breast is usually slightly more convex widthwise than is the rear end of the shank portion of the sole, the flap, unless stretched widthwise in addition to being stretched lengthwise as above described, when laid over the upper end of the heel breast, does not always extend from one side of the upper end of the breast to the other. Accordingly the operator, in addition to stretching the lateral margins of the base portion of the flap lengthwise, usually stretches the base portion of the flap widthwise.

In order to stretch the base portion of the flap 20 widthwise beyond the limit of elastic recovery of the material the matrices 32, together with corresponding clamps 34 and pads 35, are swung equal and opposite distances away from each other and from the central vertical plane 38 while they grip the respective lateral margins of the base portion of the sole as above described.

It will be noted that after the base portion of the flap 20 has been adhesively secured to the shank portion of the sole there is a tendency for the flap to shrink widthwise with the result that the sides of the shank portion of the sole sometimes project beyond the flap. In order to eliminate this undesirable condition the flap 20 is stretched widthwise by the machine forwardly approximately to its line of attachment 53 (Figs. 8, 9 and 19) with the sole.

The faces 48 of the matrices 32 are in alignment and constitute a table upon which the flap is positioned, as shown in Figs. 3 and 4. In order to assist the operator in presenting the flap 20 to the machine with its line of attachment 53 to the sole in approximate alignment with the forward edges of the faces 48 of the matrices, there is provided a rest 56. The rest 56 com-

prises plates 58 (Figs. 1 and 2) which are engaged by the heel seat of the shoe or by the heel-seat portion of the unattached sole, and a slide 60 into which are threaded screws 62 (Fig. 1) which pass through elongated slots 64 of the respective plates 58 and secure the plates in different adjusted positions to the slide 60. A groove 66 (Fig. 1) formed in the bottom face of the slide 60, is shaped to receive a rib 68 of the frame 70 of the machine, the arrangement being such that the slide may be moved into different operative positions in directions 72 after loosening a set screw 74 which passes through an elongated opening (not shown) of the frame 70 and is threaded into the slide 60. The set screw 74 is turned to bind the rest 56 to the machine frame 70 when the rest has been moved to its desired operative position.

The flat flap-engaging portions of the clamps 34 are made of rubber or other similar material which will not damage the appearance of the grain or outer side of the flap. Shank portions 76 of the clamps 34 fit in the lower ends of bores of cylindrical housings 78 (Fig. 1) which are threaded into the respective carriers 44, rotation of the clamps in their respective bores being prevented by screws 80 (Figs. 1 and 2) which are threaded into the carriers and the inner ends of which fit in vertical slots 82 of the corresponding clamps. Located in the respective housings 78 are springs 84 (Fig. 1) the lower ends of which engage the shank portions 76 of the clamps 34 and the upper ends of which are in engagement with disks 86. The disks 86 are backed up by screws 88 threaded into cap nuts 90 which in turn are threaded onto the upper ends of the respective housings 78, the arrangement being such that the clamps 34 are normally held in their lowered positions with relation to the carriers 44 by the springs 84, downward movement of the clamps with relation to the carriers being limited by the screws 80.

The carriers 44 are secured by screws 92 (Fig. 1) to arms 94 supported by fulcrum pins 96 pinned to a slide 98 which is mounted for vertical movement in guideways 100 of the machine frame 70. The slide 98 is normally held in its raised position by a spring 102 having its upper end embracing a bracket 104 secured to the main frame 70 and its lower end embracing a screw threaded onto the slide 98. Upward movement of the slide 98 is limited by a stop 106 secured to the main frame 70. The slide 98 has forwardly projecting flanges which are engaged by the arms 94 and support the carriers 44 against upward displacement during the flap-molding operation.

Secured to the slide 98 is an arm 108 (Fig. 2) through a bore 110 in the forward end of which passes a treadle-operated rod 112 (Figs. 1, 2 and 3), the upper end of the rod being enveloped by a spring 114 (Figs. 1 and 2) retained between the arm 108 and a washer 116 backed up by a screw 118 threaded onto the upper end of the rod. When the treadle rod 112 is depressed the slide 98, together with the carriers 44 which are pivotally mounted upon the slide, is lowered, causing the two pairs of clamps 34 to force the positioned flap against portions of the respective faces 48 of the matrices 32, which portions are located at opposite sides of the adjacent recesses 36 (Figs. 3 and 4). Upon continued downward movement of the slide 98 and the carriers 44 the rubber pads 35 force the lateral base portions of the flap 20 against the dished surfaces 50 of the

matrices (Fig. 5) causing said portions of the flap to be stretched lengthwise, the dished surfaces being so shaped that the stretching force applied to the flap increases progressively from the portions 119 (Figs. 8 and 9) of the flap outwardly, the greatest stretch being applied at the lateral edges of the flap.

Secured by screws 120 to each of the matrices 32 is a horizontal arm 122 which is pivotally supported at its rear end upon a fulcrum pin 124 secured to the main frame 70. The axes 126 of the fulcrum pins 96, 124 are coincident. In order to insure against straining the fulcrum pins 124 during the flap-molding operation, the main frame has secured to it a pair of plates 128 which are constantly engaged by bottom faces of the respective matrices 32.

As above stated, it is usually desirable to stretch the base portion of the flap widthwise to insure that it shall cover the upper end of the heel breast. Accordingly associated matrices 32 and carriers 44 are mounted for movement toward and away from the central heightwise plane 38 about the respective axes 126 of the fulcrum pins 96, 124. In order to move the corresponding matrices 32 and carriers 44 as units toward and away from the plane 38, the arms 122 secured to the matrices have secured to them by screws 130 upstanding bars 132 which fit in vertical slots 134 formed in the respective carrier-supporting arms 94. With such an arrangement it will be clear that when the matrices 32 are swung toward and away from each other about the respective axes 126 through mechanism which will be described later, the corresponding carriers 44 and the respective clamps 34 and conforming pads 35 mounted upon the carriers, partake of such movement.

Associated matrices 32 and carriers 44 are normally urged as units toward each other by a spring 136 (Figs. 1 and 2) the opposite ends of which are secured to the respective arms 94, movement of the units toward each other being limited by the engagement of the inner ends of screws 138, which are threaded into the arms 94, with the main frame 70. Check nuts 140 are provided for retaining the respective screws 138 in their adjusted positions in the arms 94. With such an arrangement it will be clear that the initial operative positions of the matrices 32 and the carriers 44 can be varied in accordance with the portion of the flap it is desired to stretch.

In order to swing corresponding matrices 32 and carriers 44 about the axes 126 from their inward positions shown in Fig. 5 to their outward positions shown in Fig. 6 after the lateral base margins of the flap 20 have been stretched lengthwise as above described, each of the arms 122 has rotatably secured to it a roll 142, which is constantly held in engagement with a cam 144 keyed to a shaft 146, by the spring 136. The shaft 146 is rotatably mounted in the machine frame and has secured to its right end, as viewed from the front of the machine, an arm 148 (Figs. 2 and 3) which, during a predetermined stage of the downward movement of the rod 112 is forced downward by a nut 150 threaded onto the rod to swing the arm 148 downward, thereby swinging the cams 144 in counterclockwise directions, as viewed in Fig. 2, and causing the arms 122 to which the matrices 32 are secured to move equal distances away from the central vertical plane 38 about the respective axes 126 of the fulcrum pins 96, 124. Outward swinging movement of the respective matrices 32 and their asso-

ciated carriers 44 away from the plane 38 is limited by the engagement of the right cam 144 (Fig. 2) with a plate 152 which may be secured through a screw-and-slot connection 154 in different heightwise positions to the main frame 70.

In order to insure against the molded flap entering between the matrices 32 as the same are swung from their outward positions shown in Fig. 6 to their initial positions, the carriers 44 are raised suitable distances away from respective matrices 32 to enable the operator to remove the shoe being operated upon from the machine, before the matrices and their associated carriers are swung inwardly toward each other. Accordingly, the shaft 146 has secured to its left end, as viewed in Fig. 1, a ratchet arm 156 which, during the outward swinging movement of the matrices 32 and the carriers 44, is swung upwardly so that its teeth 157 engage a pawl 158 which is pivoted upon a pin 168 secured to the machine frame and is normally urged forwardly by a spring 162. Forward movement of the pawl 158 is limited by the rear face of a cam 164 which is secured by a screw to the slide 98. When the slide 98 is lowered, causing the clamps to force the flap 20 against the faces 48 of the matrices 32 and causing the pads 35 to force the lateral base margins of the flap against the dished surfaces 50 of the matrices, the pawl 158 is permitted to swing under the action of the spring 162 to a forward position against a portion 168 of the rear face of the cam 164. Subsequently as the shaft 146 is rotated in a clockwise direction, as viewed in Fig. 1, causing the matrices 32 and corresponding carriers 44 to be swung about the axes 126 away from the central heightwise plane 38 of the machine, the teeth 157 of the ratchet arm 156 engage the pawl 158 which prevents the ratchet arm from moving downward and the matrices 32 and corresponding carriers 44 from being swung toward each other from their outward positions shown in Fig. 6 until a shoulder 170 of the cam 164 swings the pawl rearwardly 45 out of engagement with the ratchet arm. After the ratchet arm 156 has been released it drops to its initial position shown in Fig. 1 under its own weight and the spring 162 moves the matrices 32 and the associated carriers 44 back to their initial inward positions shown in Fig. 1. The shoulder 170 of the cam 164 is so arranged that upon upward movement of the rod 112 the clamps 34 and the corresponding pads 35 are raised sufficiently to release the flap before the ratchet arm 156 is released. Accordingly, the work may be removed from the machine by the operator before the matrices 32 and the corresponding carriers 44 start to swing back about the respective axes 126 to their initial positions.

It will be appreciated that if desirable the widthwise stretching of the flap may be omitted by raising the nut 150 to an inoperative position upon the rod 112. Under such conditions the matrices 32 remain stationary during the flap-molding operation and may be referred to as a matrix.

Having described the invention, what I claim as new and desire to secure by Letters Patent of the United States is:

1. A machine for operating upon heel-breast-covering flaps having, in combination, molding units constructed and arranged to stretch the lateral base portions respectively of a heel-breast-covering flap lengthwise, and means for moving

one of said units away from the other to stretch the flap widthwise.

2. In a machine for operating upon heel-breast-covering flaps, means for forming in the lateral margins of the base portion of a heel-breast-covering flap crimps which extend widthwise of the flap, each of said crimps increasing in width and height as it approaches an adjacent lateral edge of the flap, and means for stretching portions of the flap included between said crimps widthwise of the flap to increase the width of the base portion of the flap.

3. In a machine for operating upon heel-breast-covering flaps, molding units for forming in the lateral margins of the base portion of a flap crimps which extend widthwise of the flap and increase in width and height as they approach the adjacent lateral edges respectively of the flap, and means for moving one of said units with relation to the other to stretch the flap widthwise.

4. In a machine for operating upon heel-breast-covering flaps, a matrix for supporting a heel-breast-covering flap, clamping means for forcing lengthwise spaced portions of the lateral margins of the flap against the matrix, and conformable means constructed and arranged to cooperate with the matrix and the clamping means to stretch lengthwise of the flap portions of the lateral margins of the flap which are included between said lengthwise spaced portions of said lateral margins.

5. A machine for operating upon heel-breast-covering flaps having, in combination, a matrix for supporting a heel-breast-covering flap, two pairs of clamps, each pair of clamps being constructed and arranged to force lengthwise spaced portions of an adjacent lateral margin of the flap positioned upon the matrix against said matrix, and conformable means cooperating with the matrix and the clamps to stretch lengthwise of the flap portions of the lateral margins of the flap included between the clamps of each pair.

6. A machine for operating upon heel-breast-covering flaps having, in combination, a matrix for supporting a heel-breast-covering flap, said matrix having recesses which are shaped and arranged to be bridged by the lateral margins of the base portion of the flap positioned upon the matrix, clamping means for forcing the flap against portions of the matrix located at opposite sides of the respective recesses, and conformable means for forcing the lateral margins of the base portion of the flap gripped between the clamping means and the matrix into the recesses to stretch said margins of the flap lengthwise.

7. A machine for operating upon heel-breast-covering flaps having, in combination, a pair of matrices, a pair of presser units constructed and arranged to force the respective lateral base portions of a heel-breast-covering flap against the matrices to stretch said portions lengthwise of the flap, and means for moving one of the matrices and its associated presser unit with relation to the other matrix and unit to stretch the flap widthwise.

8. A machine for operating upon heel-breast-covering flaps having, in combination, a pair of matrices, a pair of presser units constructed and arranged to force the respective lateral base portions of a heel-breast-covering flap against the matrices to stretch said portions lengthwise of the flap, means for moving one of the matrices and its associated presser unit with relation to the other matrix and unit to stretch the flap width-

wise, and means for varying the amount of movement of said one matrix and its associated presser unit in accordance with the amount it is desired to stretch the flap widthwise.

5 9. A machine for operating upon heel-breast-covering flaps having, in combination, matrices having aligned substantially flat faces respectively which are initially positioned adjacent to each other and in each of which is formed a recess, 10 pairs of clamps for forcing a heel-breast covering flap against the respective faces of the matrices, conformable pads for forcing the lateral margins of the base portion of the flap gripped by the faces of the matrices and the clamps into 15 said recesses to stretch said margins of the flap lengthwise, and means for moving each of said matrices together with its associated clamps and conformable pad as a unit with relation to the other matrix to stretch said base portion of the 20 flap widthwise.

10. A machine for operating upon heel-breast-covering flaps having, in combination, a pair of matrices having faces respectively which are constructed and arranged to support a heel-breast-covering flap and in each of which is formed a recess over which a lateral base portion of the flap may be positioned, each of said recesses being of increasing width and depth as it extends away from the other recess, clamps for forcing the flap against said face of each of the matrices, conformable pads for forcing the lateral margins of the base portion of the flap gripped by said faces of the matrices and said clamps against the bottoms of the respective recesses to stretch said 35 lateral margins of the base portion of the flap lengthwise, and means for moving one of the matrices together with its associated clamps and pad as a unit with relation to the other matrix to stretch the base portion of the flap widthwise.

40 11. A machine for operating upon heel-breast-covering flaps having, in combination, a pair of matrices each having a dished surface, a pair of carriers, a pair of clamps yieldingly mounted upon each of the carriers, a conformable pad secured to each of the carriers, and means for effecting relative movement of the carriers and the matrices to cause the clamps to force a heel-breast-covering flap against the matrices and then to cause the pads to force the lateral margins of the base portion of the flap against the dished surfaces of the matrices.

45 12. A machine for operating upon heel-breast-covering flaps having, in combination, a matrix for supporting a heel-breast-covering flap, said matrix having recesses which are shaped and arranged to be bridged by the lateral margins of the base portion of the flap positioned upon the matrix, a carrier, clamps yieldingly mounted upon the carrier and constructed and arranged to force the flap against portions of the matrix located at the opposite sides of the respective recesses, conformable means secured to the carrier and constructed and arranged to force the lateral base portions of the flap gripped between the clamps and the matrix into the recesses to stretch said portions of the flap lengthwise, and means for effecting relative movement of the carrier and the matrix to cause the clamps to force the flap against the matrix and then to cause said conformable means to cooperate with the matrix to stretch the flap.

50 13. A machine for operating upon heel-breast-covering flaps having, in combination, a pair of matrices having recesses respectively which are positioned adjacent to each other and each of

which is of increasing width and depth as it extends away from the other, said matrices being constructed and arranged to support a heel-breast-covering flap with its lateral base portions bridging the respective recesses, a pair of carriers, 5 pairs of clamps yieldingly mounted upon the respective carriers, conformable pads secured to the respective carriers, and means for effecting relative movement of the matrices and the carriers to cause the clamps to force the flap against portions of the matrices located at opposite sides of the respective recesses and then to cause the lateral base portions of the flap gripped between the clamps and the associated matrices to be forced into the recesses to stretch the lateral base 10 portions of the flap lengthwise.

15 14. A machine for operating upon heel-breast-covering flaps having, in combination, a pair of matrices, a pair of presser units constructed and arranged to force the lateral base portions of a heel-breast-covering flap against the matrices to stretch said portions lengthwise of the flap, and means for initially adjusting one of the matrices and its associated presser unit with relation to the other matrix and presser unit in accordance 20 with the portions of the flap it is desired to stretch.

25 15. A machine for operating upon heel-breast-covering flaps having, in combination, a pair of matrices having faces for supporting a heel-breast-covering flap and having dished surfaces which are bridged by the respective lateral base portions of the flap positioned upon said faces, pairs of clamps for forcing the flap against said faces of the matrices, a pair of conformable pads for forcing the lateral base portions of the flap 30 against said dished surfaces of the matrices to stretch said portions of the flap lengthwise, and means for initially adjusting each of the matrices together with its associated clamps and pad to- 35 ward and away from the other.

40 16. A machine for operating upon heel-breast-covering flaps having, in combination, a pair of molding units, means for causing the molding units to stretch the lateral base portions of a heel-breast-covering flap lengthwise and then to grip said portions, means for causing one of the molding units to move from an inward position adjacent to the other unit to an outward position spaced a short distance from the other unit, and mechanism movable in response to said means for causing said one unit to be retained in its outward position until said units have released the flap, thereby insuring against the flap being damaged as said one unit is moved back to its inward position.

45 17. A machine for operating upon heel-breast-covering flaps having, in combination, a pair of matrices, presser units constructed and arranged to cooperate with the respective matrices, means for effecting relative movement of the matrices and the presser units to stretch lengthwise and to clamp the lateral base portions of a heel-breast-covering flap split from a sole, means for moving each of the matrices, together with its associated presser unit, from an inward position adjacent to the other to an outward position spaced a substantial distance from the other in order to stretch the base portion of the flap widthwise, and means for retaining the matrices and the presser units in said outward positions 50 until sufficient relative movement has been effected between the matrices and the presser units to enable the operator to remove the sole from the machine.

covering flaps having, in combination, a pair of matrices constructed and arranged to be engaged by a heel-breast-covering flap, a pair of presser units movable toward and away from the respective matrices and constructed and arranged to force the lateral base portions of the flap against the matrices thereby stretching said portions lengthwise, resilient means for normally urging each matrix and its associated presser unit inwardly toward the other matrix and presser unit, means for limiting inward movement of the associated matrices and presser

units, mechanism for moving each matrix and its associated presser unit away from the other matrix and presser unit against the action of said resilient means to their outward positions in order to stretch the base portion of the flap widthwise, and means for retaining the associated matrices and presser units in their outward positions until the presser units have been moved sufficient distances away from the matrices to enable the operator to remove the flap 10 from the machine. 5

MICHELE CUOZZO.
